UNITED STATES PATENT OFFICE

149,822

DESIGN FOR A PANTY GIRDLE

Louis P. Keller, Chicago, Ill.

Application June 15, 1946, Serial No. 130,751

Term of patent 3½ years

(Cl. D20—2)

To all whom it may concern:

Be it known that I, Louis P. Keller, a citizen of the United States and a resident of Chicago, in the county of Cook and State of Illinois, have invented a new, original, and ornamental Design for a Panty Girdle, of which the following is a specification, reference being had to the accompanying drawing, forming a part thereof.

Fig. 1 is a front perspective view of a panty girdle showing my new design;

Fig. 2 is a rear perspective view thereof, and Fig. 3 is a bottom plan view thereof.

I claim:

The ornamental design for a panty girdle, substantially as shown.

LOUIS P. KELLER.
